Primary Examiner — Ian Simmons*Assistant Examiner* — Lauren Calve(74) *Attorney, Agent, or Firm* — Stites & Harbison PLLC; Richard S. Myers, Jr.(57) **CLAIM**

The ornamental design for a shoe rack, as shown and described.

DESCRIPTION

FIG. 1 is a top perspective view of a shoe rack showing the new design;

FIG. 2 is a front elevation view thereof;

FIG. 3 is a right side elevation view thereof; the left side elevation view being a mirror image;

FIG. 4 is a rear elevation view thereof;

FIG. 5 is a top plan view thereof; and,

FIG. 6 is a bottom plan view thereof.

The broken lines shown represent unclaimed subject matter and form no part of the claimed design.
